DISPENSING CAP FOR A PRESSURIZED CAN

Garrison G. Trupp, 4600 York Road, Baltimore, Md.
21212, and Marc A. Trupp, 23 Stonehenge Circle,
Pikesville, Md. 21208

Filed Apr. 15, 1969, Ser. No. 16,755

Term of patent 14 years

Int. Cl. D9—02

U.S. Cl. D9—278

FIG. 1

FIG. 2

FIG. 3

FIG. 5

FIG. 6

FIG. 7

FIGURE 1 is an elevational view of a dispensing cap for a pressurized can showing our new design;

FIGURE 2 is a top plan view;

FIGURE 3 is a bottom plan view;

FIGURE 4 is a front elevational view;

FIGURE 5 is a rear elevational view;

FIGURE 6 is a fragmentary view of our new design showing a modified tip; and

FIGURE 7 is a view similar to FIG. 6 showing another modified tip.

We claim:

The ornamental design for a dispensing cap for a pressurized can, as shown and described.
